COMBINATION BENCH AND SEESAW PLANK

Leslie L. Westcamp, Fair Oaks, Calif.

Application February 24, 1949, Serial No. 1,045

Term of patent 14 years

(Cl. D34—5)

To all whom it may concern:

Be it known that I, Leslie L. Westcamp, a citizen of the United States, residing at Fair Oaks, in the county of Sacramento and State of California, have invented a new, original, and ornamental Design for Combination Bench and Seesaw Plank, of which the following is a specification, reference being had to the accompanying drawing, forming a part thereof.

Figure 1 is a top perspective view of the combination bench and seesaw plank, showing my new design; and

Figure 2 is a bottom perspective view thereof.

The dotted line showing of a seesaw pedestal is for illustrative purposes only.

I claim:

The ornamental design for a combination bench and seesaw plank, as shown and described.

LESLIE L. WESTCAMP.
